AIR PICKUP SYSTEM

Stuart Crosby Plummer, Wilmington, Del., assignor to All American Aviation, Inc., Wilmington, Del., a corporation of Delaware

Application December 22, 1941, Serial No. 423,999

24 Claims. (Cl. 258—1.2)

This invention relates to aviation and more particularly to devices for picking up burdens from the ground by aircraft while in flight.

According to a preferred embodiment of the invention there is provided a ground station having two poles spaced apart with a ground loop connected to the tops of the poles by releasable couplings. The ground loop forms a horizontal upper ply, and a lower ply which is connected to the burden which may rest upon the ground. The aircraft, which may be an airplane, has an arm depending from its underside which supports a hook or grapple in such position as to engage the upper ply of the ground loop as the plane is flown over the poles and between a vertical projection of the poles. A pick-up line is connected to the hook and to suitable take-up devices within the plane.

The present device is designed primarily for use on aircraft that are traveling at high speeds. Some means must be provided for absorbing the initial shock set up when the pick-up hook engages the line supporting the burden to be picked-up.

Means have formerly been used in an attempt to secure this end, but they have necessitated the addition of weight, and mechanism which can get out of order, all of which is undesirable in an aircraft. Previous devices have suggested the use of shock cord such as that used for landing gears, and various other purposes on aircraft. Shock cord is objectionable for the reason that, if it is made strong enough, and with a sufficient degree of elasticity to take up the shock of impact, the opposite and equal reaction will tend to throw the burden ahead of the line by which it was picked-up, and in some cases even to throw the burden over the top of the aircraft. The dangers inherent in such a condition are obvious. Attempts have been made to use other materials which would stretch, and have a high degree of tensile elasticity, but these materials have proven unsatisfactory for the reason that their elasticity has been such that it caused the aforeindicated results, or soon became exhausted so that it no longer performed the desired function of absorbing the shock at all.

It has been found, according to the invention, that it is desirable for a shock absorbing member to have the characteristics of high tensile strength, excellent elasticity, great elongation within its elastic limit, and long elastic memory, i. e., slow return to original length after placing under tension. It has been found, according to the invention that a line having these de-

sirable characteristics may be constructed from synthetic condensation polyamide fibers known commercially as nylon.

A line of this type may be used as the preliminary shock absorbing means in conjunction with a winch or reel which is free to rotate at the time that engagement is made with the line attached to the burden to be picked-up. The elasticity of the line will accelerate the winch or reel thereby permitting relatively heavy weights to be picked up. By virtue of a controlled braking action on the winch or reel, the acceleration placed on the burden to be picked-up, and in turn the load imposed on the pick-up line, winch, and aircraft, may be adjusted. This controlled braking action is only necessary where relatively heavy loads are to be picked-up. With smaller loads the pick-up line, or the pick-up line in combination with a ground loop, will provide sufficient energy absorbing action to permit pick-ups at relatively high speeds.

For controlling the reel, according to the invention, a small electric motor may be used, controlled by a manually operated switch operating the reel to pay out line or to reel in the line slowly or rapidly. The reel may have an acceleration-control brake element secured thereto which may apply a light load to the reel when the engagement with the load starts to unwind the reel and then, after a predetermined number of revolutions of the reel, apply full braking pressure to the reel. The full braking pressure may be so adjusted as to permit the reel to turn where the load imposed on the line would otherwise break it or damage the aircraft.

The small electric motor may drive a cooperating brake element of the acceleration-control brake to rotate the reel through a magnetic clutch, which is operated automatically to connect the motor to the brake when electricity is applied to the motor. The magnetic clutch has a second position which holds the second control brake element stationary when current is removed from the motor.

The pick-up arm may comprise a laminated pole and may be pivoted to the underside of the aircraft near the center of gravity of the craft. This arm may have a guideway on the back on which slides a carrier or cleat supporting a hook which extends from the back of the arm around the side to project out in front of the arm. The hook is provided with staggered barbs for preventing accidental disengagement of the ground loop.

The invention also consists in certain new and

original features of construction and combinations of parts hereinafter set forth and claimed.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawings forming a part thereof, in which

Fig. 1 illustrates diagrammatically an airplane about to pick up a load from the ground station, according to the invention.

Fig. 2 is a longitudinal detail section through 15 the end of the pick-up arm.

Fig. 3 is a cross-section on the line 3—3 of Fig. 1.

Fig. 4 is a transverse section through the axis of the acceleration-control reel.

Fig. 5 is a section on the line 5—5 of Fig. 4.

Fig. 6 is a detail showing the manner of connecting the pick-up line to the reel.

Fig. 7 is a side elevation of the control reel.

Fig. 8 is a detail of the pick-up hook.

Fig. 9 is a detail plan view of the pivot connection between the pick-up arm and airplane frame.

Fig. 10 is a section on the line 10—10 of Fig. 9 illustrating a bearing construction; and

Fig. 11 is a section on the line 11—11 of Fig. 9 illustrating the manner of clamping the wood pick-up arm to the metal yoke.

I wish it to be understood that I do not desire to be limited to the exact details of construction shown and described, for obvious modifications will occur to persons skilled in the art.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, and more particularly to Figs. 1 to 3 and 9-11, the aircraft is illustrated as a modern airplane indicated by 1 provided with a hatch 9 in the floor of the fuselage. Pivotally mounted at the forward side of the hatch and near the center of gravity of the plane is a yoke 10 for the pick-up arm 5. The yoke 10 has a Y-configuration and suitable pivot devices 6 may be provided for pivoting the Y branches to suitable structural members within the fuselage.

Lever 7 may be connected to yoke 10 to manipulate it. Suitable stops or catches, indicated by 8 and 8', engage with the lever 7 to lock the pick-up arm 5 in desired position. The catches 8 serve to lock the pick-up arm in approximately the position shown in Fig. 1, which is the approximate pick-up position for engaging the load. The catches 8' are for the purpose of locking the arm in position up against the underside of the fuselage.

The yoke 10 and hatch 9 are located at the side of the fuselage and the pick-up arm 5 is placed at a slight angle to the axis of pivot 6 to permit the arm to lie within the confines of the horizontal projection of the fuselage when it is folded up against the bottom of the fuselage. If desired the fuselage may be provided with a longitudinal recess indicated by 11 in Fig. 1 to receive

and partially house the pick-up arm 5 in retracted position.

The yoke 10 is of Y or triangular configuration, comprising an axle member 12 and two diagonal members 13 suitably welded thereto. The axle member extends across the hatch 9 and rests on suitable seats on the structural members 14 secured to the fuselage, the seats having removable straps 22 and forming bearings for the pick-up arm (Fig. 10).

The pick-up arm 5 is clamped to the yoke member 10 by suitable clamps 23, each clamp comprising a seat secured to the yoke member and a removable strap for clamping the arm in its seat (Fig. 11). If desired, suitable cushions such as leather sleeves 24 may be interposed between the wooden pick-up arm 5 and the clamps 23 to prevent damage to the wood by the clamps.

The winch 61, on which a suitable amount of pick-up line 2 is wound, is preferably mounted forward of the hatch 9. This line is preferably unwound from the afterside of the winch 61 to facilitate removing the burden from the pick-up rigging when the winch is wound up to bring the burden into the plane as will hereinafter more clearly appear.

The pick-up arm 5 comprises a shaft which may be of the order of 15 feet in length. This shaft is made of comparatively light strong material and may be formed of a comparatively heavy forward section 15, which may be of oak or other suitable sturdy material, and a laminated after-section 16 which may be of somewhat lighter material, such as spruce wood. The shaft may be tapered, gradually decreasing in size from its upper to its lower end.

Secured to the afterside of the after-section of the pick-up arm 5 is a track 17 which may comprise a metal strip suitably shaped to space its edges from the body of the pick-up arm and suitably secured to the pick-up arm as by screws 41. Slidably mounted on the track 17 is a cleat or slider 18 having suitable flanges 19 extending around the edges of the track 17 to insure easy permanent sliding action. The upper end of track 17 is free of abutments and bends away from the pick-up arm as at 42 and is secured to yoke 10 by a strut 43. Portion 42 permits the operator to put the cleat onto the track in the beginning of the picking-up operation, as is explained hereinafter. The lower end of the track 17 is provided with spring detents 20 and 21. The first detent 20 permits the cleat to pass readily over it due to action of gravity and of the air stream but to restrict its return. The action of the lower detent 21 holds the cleat in operative position until it is forcibly removed from the track by the picking-up operation.

The provision of a heavy forward section and a lighter laminated after-section insures that the center of gravity of the cross-section of the pick-up arm is forward of its center of area and this, together with the laminated construction, prevents flutter and gives smooth operation.

The hook 3 is secured to the cleat 18 and is provided with a curved shank 29 passing from the rear of the pick-up arm around the side to the front thereof and ending in a bill 25 provided with staggered barbs 26 and 27. The hook is also provided with an eye 28 to which the line 2 is attached. By extending the bill 25 of the hook forward of the pick-up arm the load may be picked up without introducing any turning or twisting action on the pick-up arm and the staggered barbs 26 and 27 prevent accidental disen-

agement of the ground loop from the hook after engagement as explained hereinafter. This type of hook also makes it possible to have the track on the back of the pick-up arm where the track will not be damaged by contact with the pick-up loop nor will it be so free to accumulate ice or dirt.

The ground station may comprise two poles 30 set in the ground a suitable distance apart, say 20 feet, and having a suitable height, say 20 feet, to the upper end of which may be connected flags 36. The corners of the flags 36 may be provided with releasable couplings 35 which engage ground loop 31 having an upper ply 32 suspended between the poles and a lower ply 33 connected to the burden 34 which may rest upon the ground.

Referring now to Figs. 4-7, the control device for paying out or drawing in the transfer line 2 comprises generally the winch 61, an automatic brake 80 operative to place the maximum desired braking effort upon the winch upon a predetermined number of revolutions thereof, an electric motor 160 for driving the winch and an electromagnetic clutch 168. The control device includes a frame 50 suitably secured to the frame of the airplane, and which supports the winch 61.

The transfer line 2 is attached at one end to the winch 61, preferably by a connection which will permit the end to be released in the event of emergency. Referring to Fig. 6, the end of the line 2 is secured in a socket 200 threaded on a stud 201 carried by or formed integral with a weakened stem 202. The stem 202 is carried by and preferably integral with a bracket 203, attached as by bolts to one of the flanges of the winch 61. The transfer line 2 extends through the hatch 9 in the bottom of the aircraft to the hook 3 located at the end of the slide on arm 5 in Fig. 1.

The winch 61 is fixedly carried by a shaft 62 journaled at one end in a bearing 63 mounted in the side wall 48 of the frame 50 and provided with a seal 65 and a cover 66. The winch 61 includes a cylindrical rim 67 connected by a web 68 to a hub 69 and has at one end a retaining flange 71. A second retaining flange 72 is attached to the rim 67 as by bolts 73. The reel 61 is suitably secured against axial or angular displacement on the shaft 62 and abuts a positioning shoulder 74. Annular extensions 70 are secured to flanges 71 and 72 to provide for desired number of turns of line 2.

A brake plate 75 is attached to and carried by the winch 61. The brake plate 75 is provided with a plurality of circumferentially spaced lugs 76 which are set in notches 77 formed in lugs 78 which extend inwardly from the cylindrical portion 67. The plate 75 thus is capable of moving axially but is locked against angular movement relative to the winch 61.

The brake 80 cooperates with the brake plate 75 and includes a driving brake disc or frame 81 having a suitable friction lining 82 secured to its face and adapted to bear against the brake plate 75. The brake disc 81 is carried by (and in the present embodiment is integral with) a hub 83 which carries a bearing 84 mounted on the shaft 62 and retained by a ring 85.

The hub 83 has a journal and bearing portion 86 which receives a bearing 88 positioned by a ring 89. A sleeve 89 abutting a shoulder 90 on the shaft assists in positioning the bearing 88 on the shaft 62. The bearing and journal portion 86 is itself journaled in a bearing 87 mounted in the side wall 48 of the frame 50 and secured by 70

a ring 85. Thus the bearing 87 constitutes with the bearing 63 the main bearings for supporting the shaft 62 rotatably in the frame 50.

Cooperating with the brake disc 81 is a complementary brake disc or shoe 92 of annular form having frictional lining 93 on its face bearing against the brake plate 75. The brake disc 92 is resiliently urged lightly toward the brake plate 75 by bolts 210 extending through the brake disc 92, the interior opening of the ring 75 and through a suitable opening in the brake disc 81. Bolts 210 carry springs 212 bearing against the brake disc 81 and against an adjusting nut or nuts 213.

Extending from the brake disc 92 is a plurality (in the present case 3) of studs 94 which extend through openings in the brake disc 81. Pivottally connected to each stud 94 by a pivot pin 95 is an operating lever 96 which carries at the end of its shorter arm a roller 97 adapted to bear against a box 99 projecting from the adjacent face of the brake disc 81. The long arm end of the actuating lever 96 is pivotally connected as by a pivot pin 100 to a socket 101 attached to an actuating rod 102 which extends through the journal and bearing portion 86. The actuating rod 102 is connected by a spring 103 to a stud 104 which is threaded into a disc 105.

Upon movement of the disc 105 (effected in a manner hereinafter to be described) in a direction away from the brake disc 81 (to the right as viewed in Fig. 4) the actuating rods 102 are moved in a similar direction to thereby rock the levers 96 causing the rollers 97 to bear upon their respective bosses 99 and to clamp the brake disc 92 and the brake disc 81 against the brake plate 75. Owing to the lug and notch connection between the brake plate 75 and the reel 61, the brake is thereby permitted to shift axially and allow the clamping action to take place.

In order to cause the actuating disc 105 to move outwardly and to apply the brake 80 upon a predetermined number of revolutions of the winch 61, an automatic brake actuating mechanism is provided which will now be described.

The disc 105 is non-rotatably connected to the journal and bearing member 86 by a stud 110 which extends through the disc 105 and is threaded into the member 86. The disc 105 is mounted on a collar 111 having a flange 112 at one end and a ring 113 at the other end, the disc 105 and collar 111 being thus permitted to have relative axial sliding movement which is limited in extent by the flange 112 and ring 113.

The collar 111 is adjustably threaded onto an outer sleeve 114 and is positioned non-rotatably thereon by a spring 115 adapted to enter into any one of a plurality of circumferentially spaced, axially extending notches or slots 116. The spring 115 can be raised out of its notch and the collar 111 turned in the outer sleeve 114 to adjust the axial position of the collar 111 and thereby adjust the time at which the flange 112 strikes against the disc 105.

The outer sleeve 114 is threaded onto an inner sleeve 117 by large screw threads which permit the sleeve 114 to turn on the inner sleeve 117 and to be advanced thereby in an axial direction. The inner sleeve 117 is non-rotatably secured to the shaft 62 as by a key 118.

Movement of the sleeve 114 on the inner sleeve 117 is limited by a flange 119 at the inner end of the inner sleeve 117 and by a ring 120 non-rotatably secured on the shaft 62 as by a key 121 and a nut 123 and abutting the outer end of the sleeve

117. In order to permit axial movement of the outer sleeve 114 on the inner sleeve 117, a recess 124 is formed in the outer sleeve 114 of sufficient diameter to accommodate the ring 120. For the purpose of manually turning the outer sleeve 114 (for resetting purposes hereinafter described), a flange 122 is provided at its outer end having sockets 125 for a spanner.

In order to provide a suitable braking action or drag on the outer sleeve 114 to prevent it from rotating except when desired, a friction brake may be provided. The friction brake includes brake ring 130 which surrounds the outer sleeve 114 and preferably seats in a circumferential groove 134 to prevent displacement of the ring 130, a suitable brake lining 133 being provided. The brake ring 130 is formed with a lug or extension 131 having an opening through which the stud 110 loosely passes whereby the brake ring is non-rotatably connected to the member 86.

For a more complete description of the winch and automatic control therefor attention is called to my application Serial No. 333,081 filed May 3, 1940, entitled Transfer apparatus.

It will now be seen upon rotation of the shaft 62 which carries the winch 61, the inner sleeve 117 is rotated correspondingly and through the action of its threads causes the outer sleeve 114 to be moved axially in a direction away from the frame member 49 (to the right, as viewed in Fig. 4). As the outer sleeve 114 moves outwardly, the flange 112 is brought into abutment with the disc 105 and moves it in a corresponding direction, thereby exerting a pull on the several actuating rods 102 and causing the brake disc 92 and the brake disc 81 to clamp more tightly against the brake ring 75. The brake 80 therefore is automatically applied with continuously increasing force until the winch 61 is halted or until the end of the socket or recess 124 abuts the ring 120.

In order to rotate the winch 61 so as to draw in or pay out the transfer line 2, suitable rotating means are provided, which in the present case, comprise a driving motor 160 connected to the brake 80. A drive gear 150 is rigidly secured to the brake disc 81 as by bolts 151 and a driving pinion 152 meshes with the gear 150. The driving pinion is carried on a shaft 153 of reduction gearing denoted in general by 154 and secured to the frame member 50.

The reduction gear 154 comprises a worm wheel 155 on shaft 153, wheel 155 being driven by worm 156 which is connected to gear 157 and suitably journaled in the gear box. Gear 157 is driven by pinion 158 mounted on axially slidable shaft 163. The reduction gear may be of high speed ratio, the total ratio between motor 160 and winch 61 being of the order of 220 to 1.

The electric motor 160 may be of a high speed type. Located between the motor 160 and the reduction gear 154 is the electro-magnetic clutch and brake 166 indicated diagrammatically in Fig. 7. This clutch and brake may comprise a brake disc 161 suitably secured to the casing of the clutch and a disc 162 mounted upon the slidable shaft 163. The motor shaft 164 may have an electro-magnetic disc 165, which is magnetized by solenoid winding 167a when electric power is applied to the motor 160.

When no electricity is applied to winding 167a, the disc 162 is held against the brake surface on disc 161 by a spring disc 168 acting between a plate 169 fixed to the casing and a slidable plate

170 set in a groove 159 in slidable shaft 163, which effectively locks shaft 163.

When electric power is applied to motor 160, the electro-magnetic disc 165 is automatically energized which exerts a magnetic pull on disc 162, axially sliding it together with shaft 163 and gear 158, freeing disc 162 from brake element 161 and engaging it with element 165 to exert driving power upon shaft 163 to drive the winch 61 in either direction.

Due to the high reduction of gear reducer 154 a small braking effort is sufficient to hold the gear 150 and brake 80 stationary. The electro-magnetic brake 161, 162 also acts to bring winch gear 150 quickly to rest when electric current is removed from motor 160. In some cases, when a sufficiently low pitch worm is used in the reduction gear 154, the brake 161, 162 may be dispensed with entirely.

20 A five position push button control indicated in general by 167 on the top of frame 50 is provided for electrically controlling motor 160 and electro-magnetic clutch 166. The control 167 has five positions, one of which is "neutral" which entirely removes all power from the electric motor and clutch. Second and third positions are for slow and rapid "reverse" respectively for causing the motor to drive the winch 61 in such direction as to pay out line 2 slowly or rapidly. The fourth and fifth positions are for slow and rapid "forward" respectively for causing the motor to power drive the winch 61 to reel in line 2 slowly or rapidly, depending upon the weight of the burden as compared to the power of the motor.

30 It will be understood that the push button control 167 is connected to a suitable source of electric power (not shown) and to the electric motor 160 and to the clutch 166 through suitable wiring and motor speed regulating devices (not shown).

Operation and comments

To use the pick-up system, the ground loop 31 is engaged with the releasable couplings 35 on the tops of the poles 30 and the burden 34 is connected to the ground loop, the burden resting on the ground. The plane is preferably provided with a pick-up operator in addition to the pilot.

The pick-up operator, before approaching the ground station, gets his pick-up apparatus in readiness for the pick-up operation. He lowers his pick-up arm slightly from its inoperative position up against the fuselage, he puts the cleat 18 on the upper end of the track 17 and operates the electric control 167 to drive motor 160 to pay out enough line 2 to allow gravity assisted by the air stream to pull the cleat down to the position shown in Fig. 1 between detents 20 and 21.

He also may adjust nuts 212 to give the desired frictional resistance between brake elements 92, 75, and 81. This sets the resistance applied to the winch 61 for the initial relatively free revolutions it will make after the load is engaged. He may also adjust sleeve 114 to reset the brake (sleeve 114 having been brought against shoulder 120 by a previous pick-up operation) and to control the maximum braking effort it is desired to impart to the winch for the picking up operation. He also may adjust the collar 111 to set the number of relatively free turns the winch will make after engagement by the load before applying tension to springs 103 to apply the brake 80.

It will be understood that when the winch 61 is positively driven by the electric motor 160 in

either direction, no relative movement takes place between the main brake elements 92, 75 and 81 and consequently no variation in braking friction is caused. It is only when the electric motor is stationary and the driving brake element 81 is held stationary that rotation of the winch causes any change in braking function on main brake 80. This condition occurs when the reel is forcibly unwound by pick-up line 2 due to engagement of the pick-up hook 3 with the ground loop 31.

Continuing with the pick-up operation, the pick-up operator then lowers the pick-up arm to a position approximating that of Fig. 1 and the pilot of the plane brings the plane over the ground station with the arm directed between the poles 30 in such manner as to engage the pick-up arm with the upper ply of the ground loop above the hook. The ground loop then slides along the smooth front face of the pick-up arm until it engages the hook, the force of contact pulling the hook free of the pick-up arm and causing the pick-up line automatically to pay out and off winch 61.

At the moment of impact of the hook with the ground loop the reel may rotate about one turn under light friction and then gradually to apply the brake 80. After, say, three more revolutions the brake may become fully applied.

At this point, the pick-up line 2 may be payed out about 30 feet, i. e., about 18 feet or more has been payed out at the time of engagement of the hook with the ground loop and the four revolutions of the drum act to pay out about 12 more feet. If the load is heavy enough, the drum will continue to pay out with the brake fully applied. With light loads there may be no further paying out after the brake is fully applied.

The action of the winch and the of the nylon pick-up line and nylon ground loop on the burden is as follows. At the moment of impact of the hook with the ground loop, the plane may be traveling 120 miles per hour, and it is desired to accelerate the burden from zero velocity to the velocity of the plane with as little shock on the plane, burden and equipment as possible. This can be done by making the acceleration of the burden as slow as possible. The elongation of the nylon rope and the payng out of the drum cooperate to this end.

Upon the first force being applied to the pick-up line 2 due to contact of hook 3 with ground loop 31, which may be considerable even with light loads and with light equipment, due to the high speeds of aircraft travel, the nylon exerts an accelerating force on the winch. The great elongation of the nylon gives time to overcome the inertia of the winch and to start it rotating. After the winch is accelerated, the brake is gradually applied to the winch to prevent too rapid payng out of the line 2 and to continue applying an accelerating force to the burden. The continuing of the payng out even after the brake is fully applied limits the force applied to the line 2 and permits the picking up of loads heavier than would otherwise be possible.

After the nylon is fully elongated, it tends to return to its original length but its elastic memory is so long and its return so slow that no overshooting, rebounding or "slingshot" action is imposed on the burden.

After the burden is accelerated to the speed of the plane, the pick-up operator then operates the take-up switch 167 to reel in the line fast or slow, depending upon how heavy the load. If

the load is sufficiently light, he reels it in fast until the burden approaches the plane after which he operates take-up switch 167 to maneuver the burden close to the reel within the plane. The control switch 167 is then placed in neutral position, stopping the reel and holding the burden stationary, after which the burden is manually lifted inside the plane. The reel may be operated to unwind the ground loop so it may be detached from hook 3 and to put the reel in readiness for the next picking-up operation.

Thus, a pick-up system has been described which is efficient and reliable in operation. The use of a light weight, stretchable, slow recovery pick-up line permits the picking up of any load the plane can handle without shock and eliminates all spring and slider devices. When used with the pay-out drum, the elongation of the nylon acts to reduce stress on the line during the period in which the drum is getting up to speed. By varying the braking effort on the drum the acceleration of the load can be nicely controlled.

Although nylon has been given for purposes of illustration, as constituting the best material known to me at the present time, for the pick-up line 2 and ground loop line 31, it will be understood that the invention is applicable to any material which has similar shock-absorbing properties. Such a material must have a substantial elongation under stress, for example in the range of from 10% to 30% elongation, it must also have the property of slowly returning the energy stored up in the line by the stress causing the elongation, i. e., long elastic memory. "Slingshot" action, i. e., overshooting of the burden with attendant slackness on the pick-up line is thus avoided. However, the material must have the property of returning to its original length within a short time. The elongation must not be permanent.

Nylon fibers, from which the pick-up rope and ground loop are made, are a well-known product manufactured and sold by E. I. du Pont de Nemours & Co. Nylon is known as a synthetic linear condensation polyamide, capable of being drawn into pliable strong fibers showing by characteristic X-ray patterns orientation along the fiber axis. This material is disclosed in Carothers Patents Nos. 2,071,250; 2,071,251; 2,130,523 and 2,157,116.

Nylon fibers have high tensile elasticity, high bending elasticity and a relatively long elastic memory. The nylon fibers are formed into yarns and the yarns may be braided to form the nylon line. The braiding operation bends the fibers, putting them into wavy configuration. When stress is applied to the line, the nylon yarns will change both their wavy configuration and length.

By tensile elasticity is meant the ability of a fiber when elongated to recover to its original length, or substantially its original length, when released from tension. This tensile elasticity is expressed in terms of elongation without destruction, and the percent of recovery within a given time. Bending elasticity as herein used means the ability of a fiber, after it has been braided into a pattern which gives it a wavy shape, to return to its original shape. For example, assume a fiber is given a form such as that usually shown to describe a wave movement; if, after being placed under tension, this fiber not only resumes its length, but also its original wavy shape, it would have, as the terms are herein used, both tensile elasticity and bending elasticity. Its elastic memory is then measured in terms of the time

that it requires for the individual fiber to resume its original or substantially its original condition before that tension was applied to it.

Nylon fibers, when first formed from solution or melt, have the peculiar characteristic of being capable of being stretched to many times their original length without exhibiting any substantial tendency to return when tension is released. When subjected to sufficient cold drawing, however, the fibers acquire an excellent elasticity, that is, tendency to return to original condition after stretching. For this reason before braiding the fibers into a line it is necessary that they be sufficiently cold drawn to the point where they exhibit such excellent elasticity.

Another advantage of the use of a line of this type is that it is moisture repellent, and, therefore, may be used where there is rain without the moisture affecting the qualities of the line. Further, such a line will not tend to accumulate ice internally when passing through icing conditions. Other materials which tend to absorb water will hold the water within the fibers of the line, and due to the movement through the air, this water and the entire line may be cooled to a point where the water will freeze, thereby restricting the action of the fibers, and preventing their proper function. In addition, a line comprised of the material herein proposed is not affected markedly by changes in temperature. A further advantage of the line is that, where used for a pick-up loop, it may be dropped on the ground without regard to ground conditions whereas ordinary line would tend to accumulate mud and dirt.

The placing of the pick-up pole or arm near the center of gravity of the plane puts the equipment and locates the pick-up operator at the most advantageous position with respect to the operation of the plane. The location of the arm forward also allows room to swing the arm up against the fuselage when it is folded out of use. The use of the laminated pole greatly increases the strength of the arm and helps eliminate flutter. The placing of the center of gravity of the pole forward of the center of area also eliminates flutter.

The placing of the guideway on the back of the arm leaves the front leading edge smooth for more efficient engagement of the ground loop. It also prevents dirt getting into the guideway when the ship is on the ground and reduces the opportunity for ice to form. The extending of the hook around to the front of the arm is accomplished without affecting the line of action of the hook or causing twisting stress on the arm. The staggered barbs on the end of the hook prevent accidental disengagement of the pick-up loop. The location of the pick-up line on the after side of the winch permits winding of the line to bring the burden further into the plane, facilitating handling of the burden by the pick-up operator.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a pick-up system, a line having the characteristic of high tensile strength, excellent elasticity, relatively great elongation, and long elastic memory, a burden, an aircraft, and means for engaging said burden from said aircraft in-

cluding a sufficient length of said line to prevent substantial rebound of said burden.

2. In an air pick-up system, a line comprising a synthetic plastic material having the inherent characteristic of high tensile strength, excellent elasticity, relatively great elongation and long elastic memory, a burden adjacent the earth, an aircraft, and means for engaging said burden from said aircraft while in flight including a sufficient length of said line to prevent substantial rebound of said burden.

3. In an air pick-up device, a ground station comprising spaced poles, releasable connections secured to said poles, a ground loop line secured to said releasable connections, said ground loop line having an upper ply extending between the tops of the poles and a lower ply, a burden secured to said lower ply, an aircraft, a pick-up line depending from said aircraft, a grappling device on the end of said pick-up line adapted to engage said upper ply, at least one of said lines comprised of a material having sufficient stretch, upon the upper strand being engaged by said grappling device, to permit gradual acceleration of said load and having sufficient energy absorption and sufficiently slow return to prevent rebound of said burden.

4. In a pick-up system, an aircraft, a burden to be picked-up by said aircraft while in flight, a winch comprising a frame, a drum journaled in said frame and having a first braking element secured thereto, a driving member also journaled in said frame and having a second braking element cooperating with said first braking element, a reduction gear driving said driving member, a high speed electric drive motor, an electro-magnetic clutch interposed between said electric drive motor and said reduction gear, said clutch acting to drive said reduction gear when electric power is applied to said motor and holding said reduction gear stationary when electric power is removed from said motor.

5. In a launching system, an aircraft, a burden to be accelerated by said aircraft, a winch comprising a frame, a drum journaled in said frame and having a first braking element secured thereto, a driving member also journaled in said frame and having a second braking element cooperating with said first braking element, a reduction gear driving said driving member, a high speed electric drive motor driving said reduction gear, and an electromagnetic clutch to hold said driving member stationary when no electric power is applied to said motor.

6. In a system for launching an object to be pulled through the air, a towing craft, an object to be towed, a line for connecting said craft and said object, said craft and object having widely different speeds of movement thereby impressing a sudden pull on said line, said line having the characteristics of high tensile strength, excellent elasticity, relatively great percentage elongation, and long elastic memory, whereby said line absorbs the shock, due to the sudden pull imposed thereon, without substantial rebound of said object.

7. Apparatus according to claim 6 in which at least a part of said line is composed of nylon fibers.

8. In a system for launching an object to be pulled through the air, a towing aircraft, an object to be towed by said aircraft, a line for connecting said craft and said object, said craft and object having widely different speeds of movement at the

time said line becomes taut, said line being made from a material whose fibres have the characteristics of high tensile strength, excellent elasticity, 10 to 30 per cent elongation, and long elastic memory, said line absorbing the shock, due to the sudden pull imposed thereon, without substantial rebound.

9. Apparatus according to claim 8 in which at least a part of said line is composed of nylon fibers.

10. In an air launching system, an aircraft, an object to be accelerated by said aircraft, apparatus for establishing connection between said aircraft and said object including a line, a winch on which a length of said line is wound, means for applying a retarding force to said winch, said line having the characteristics of high tensile strength and relatively great percentage elongation and long elastic memory so as to minimize the shock necessary to overcome the inertia of said winch, the retarding force of said winch thereafter acting to apply accelerating force to said object as said winch unwinds.

11. In an air launching system, an aircraft, an object to be accelerated by said aircraft, apparatus for establishing connection between said aircraft and said object including a line, a winch on which a length of said line is wound, means for applying a retarding force to said winch, said line having the characteristics of high tensile strength, excellent elasticity, relatively great percentage elongation, and long elastic memory, said line absorbing the shock necessary to overcome the inertia of said winch without substantial rebound, the retarding force of said winch thereafter acting to apply accelerating force to said object as said winch unwinds.

12. In an air pick-up system, an aircraft, an object to be picked up by said aircraft while the latter is in flight, apparatus for establishing connection between said aircraft and said object including a line, a winch mounted on said aircraft, means for applying a retarding force to said winch, said line having a length wound on said winch and a length connected to said object, at least a part of said line being made from a material whose threads have the permanent characteristics of high tensile strength, excellent elasticity, at least ten per cent elongation, and long elastic memory, said line absorbing the shock necessary to overcome the inertia of said winch without substantial rebound, the retarding force of said winch thereafter acting to apply accelerating force to said object as said winch unwinds.

13. In an air pick-up system, an aircraft, an object to be picked up by said aircraft while the latter is in flight, apparatus for establishing connection between said aircraft and said object including a line, said line comprising a length in the form of a loop connected to said object, a winch on said aircraft comprising a framework secured to the aircraft, a brake support rotatably mounted on said framework, a drum also rotatably mounted on said framework, a main brake acting between said support and said drum, an electric motor, gearing between said electric motor and said brake support, a motor brake for holding said brake support stationary, a unitary, rigid, smooth pick-up arm, means pivoting said pick-up arm to said aircraft near said winch, a track extending the length of said pick-up arm on the rear side thereof, a cleat slidable on said track and carrying a hook, said arm carrying yieldable means for permitting said hook to dis-

engage itself from said arm upon contact with said loop, said track having a portion at its upper end accessible for placing said cleat on the track, said line including a length wound on said drum

5 and secured to said cleat whereby said smooth unitary arm may engage said loop and guide the same into said hook, the hook thereupon disengaging itself from said arm, the pull of said object unwinding the length of said line from said drum, said line having the characteristic of high tensile strength, relatively great percentage elongation with long elastic memory.

10 14. In a system for pulling an object through the air, a pulling craft, a towed air-borne object, 15 a line connecting said craft and said object, said line having the characteristics of high tensile strength, high elasticity, 10 to 30 per cent elongation, and long elastic memory, whereby said line absorbs shock due to sudden pull imposed thereon 20 without substantial rebound of said object.

15. Apparatus according to claim 14 in which at least a part of the line is composed of nylon fibers.

16. In an air pick-up system, an aircraft, an 25 object to be picked up by said aircraft in flight, apparatus for establishing connection between said aircraft and said object including a line, said line comprising a length in the form of a loop connected to said object, a winch on said aircraft 30 comprising a framework secured to the aircraft, a brake support rotatably mounted on said framework, a drum also rotatably mounted on said framework, a brake acting between said support and said drum, means for holding said brake support stationary, a unitary, rigid, smooth pick-up arm, means pivoting said pick-up arm to said aircraft, a hook detachably supported by said arm, said line including a length wound on said drum and secured to said hook whereby said smooth unitary arm may engage said loop and guide the same into said hook, the hook thereupon disengaging itself from said arm, the pull of said object unwinding the length of said line from said drum against said brake, at least one of said 35 lengths of line having the characteristics of high tensile strength, excellent elasticity, 10 to 30 per cent elongation, and long elastic memory, whereby energy to said line is dissipated.

40 17. Apparatus according to claim 16 in which at least a part of the line is composed of nylon.

18. In a shock absorbing system, first and second elements having different motions, connecting apparatus comprising a winch mounted on one of said elements and a line connecting said winch 45 and said other element, said winch comprising a frame, a support on said frame, a drum journaled in said frame, said line being wound on said drum, a brake between said support and said frame, means controlled by rotation of said drum for gradually applying said brake from a relatively small value to full value, said line having the characteristics of high tensile strength, excellent elasticity, relatively great elongation, and long elastic memory, the pull of said line on said drum unwinding said drum, the elongation of said line minimizing the shock necessary to overcome the inertia of said drum without substantial rebound while said drum is accelerating and the braking effort is being gradually applied thereto, the full retarding force of said brake thereafter acting to apply accelerating force to said line.

50 19. Apparatus according to claim 18 in which at least a part of the line is composed of nylon.

70 20. In an air pick-up system, an aircraft, an

object to be picked up by said aircraft while the latter is in flight, apparatus for establishing connection between said aircraft and said object including a line, said line comprising a length in the form of a loop connected to said object, a winch on said aircraft comprising a framework secured to the aircraft, a brake support rotatably mounted on said framework, a drum also rotatably mounted on said framework, a main brake acting between said support and said drum, means for holding said brake support stationary, said line also comprising a second length wound on said drum, means controlled by pull on said second length of line for gradually applying said brake to said drum from a condition where said drum rotates relatively free of said brake to condition of full braking effort applied to said drum, a hook secured to said second length of line and adapted to engage said loop for the pick-up, said line having the characteristics of high tensile strength, excellent elasticity, 10 to 30 per cent elongation, and long elastic memory, the pull of said line on said drum unwinding said drum, the elongation of said line minimizing the shock necessary to overcome the inertia of said drum without substantial rebound while said drum is being accelerated from rest and the braking effort is being gradually applied thereto, the full retarding force of said brake thereafter acting to apply accelerating force to said object as said drum further unwinds.

21. In a system for changing the velocity of an object, an object of substantial mass subject to motion, a body of substantial mass with respect to which said object has relative motion, a line for connecting said body and said object, said line being subject to pull to resist said relative motion, said line having the characteristics of high tensile

strength, high elasticity, relatively great percentage elongation, and long elastic memory, whereby said line absorbs shock due to sudden pull imposed thereon by the inertia of said object without causing substantial rebound of said object.

22. In a shock absorbing system, first and second elements having different motions, connecting apparatus comprising a winch mounted on one of said elements and a line connecting said 10 winch and the other element, said winch including a drum, means for applying a retarding force to said drum, said line having a length wound on said drum, said line including a length having the characteristics of high tensile strength, excellent 15 elasticity, relatively great percentage elongation and long elastic memory, the pull of said line unwinding said drum, elongation of said line minimizing the shock necessary to overcome the inertia of said drum without substantial rebound 20 while said drum is accelerating, the retarding force of said winch thereafter acting to continue to apply force to said line.

23. In a system for launching an object to be pulled through the air, a towing aircraft, an object to be towed by said aircraft, and a line for connecting said aircraft and said object, said aircraft and object having different speeds with respect to each other thereby impressing sudden pull on said line, said line having the characteristics of high tensile strength, at least ten per cent elastic elongation and long elastic memory whereby said line absorbs the shock due to the sudden pull imposed thereon without substantial rebound of said object.

30 24. Apparatus according to claim 23 in which at least a part of the line is composed of nylon fibers.

STUART CROSBY PLUMMER.
